CLAIM

The ornamental design for a display screen or portion thereof having a graphical user interface, as shown and described.

DESCRIPTION

The sole FIGURE is a front view of a display screen or portion thereof having a graphical user interface showing my new design.

The outermost broken-line rectangle depicts the perimeter of a display screen or portion thereof having a graphical user interface and forms no part of the claimed design. The remaining broken lines depict portions of a graphical user interface and form no part of the claimed design.

1 Claim, 1 Drawing Sheet

The screenshot displays the Splunk mobile application interface. At the top, there is a navigation bar with icons for back, forward, and search. The main screen is divided into several sections:

- Search:** A search bar with a magnifying glass icon.
- Dashboard:** A circular icon with a grid pattern.
- Overview:** A section with a blue header containing the text "Monitor your home".
- Content:** A section with a blue header containing the text "Recent activity".
- Preferences:** A section with a blue header containing the text "Recommended Apps".
- Alerts & Notifications:** A section with a blue header containing the text "Unresponsive Agents".
- System Status:** A section with a blue header containing the text "Service desk team".
- Customize:** A section with a blue header containing the text "Recent activity".
- Activity feed:** A list of recent activities with small circular icons and text descriptions.
- Recent activity:** A list of recent activity items with small circular icons and text descriptions.
- Monitor your home:** A large section showing a line graph and a table of data. It includes buttons for "View Agents" and "Recent Agents".
- Recommended Apps Based on Your Activity:** A section showing recommended apps with small icons and text descriptions.
- Getting Started - Create and setup a Workspace:** A section showing a workspace setup with small icons and text descriptions.
